UNITED STATES PATENT OFFICE.

JOHN L. GUERRANT, OF SEDALIA, MISSOURI.

FREIGHT-CAR DOOR.

1,407,064.

Specification of Letters Patent. Patented Feb. 21, 1922.

Application filed April 29, 1919. Serial No. 293,436.

To all whom it may concern:

Be it known that I, JOHN L. GUERRANT, a citizen of the United States, and residing at Sedalia, in the county of Pettis and State of 5 Missouri, have invented certain new and useful Improvements in Freight-Car Doors, of which the following is a specification.

The present invention relates to freight car doors, and aims to provide means for 10 mounting a freight car door and holding and guiding it at the side of the car, in order that the door can slide open in the usual way, with the added advantage that the door can swing outwardly away from the door opening, such as when the merchandise in the car 15 presses or jams against the door preventing the same sliding open.

With the ordinary sliding door, it is frequently the case that the merchandise or 20 contents of the car in being jostled about, will jam or wedge against the door, preventing the door being slid open, and crow bars and other implements are generally used for 25 prying the door open, resulting in damage to the car and door and sometimes to the merchandise. This invention resides in the mounting of the door for sliding movement and also permitting the door to swing outwardly when necessary, with novel means 30 for ordinarily holding the lower edge of the door against the wall of the car and guiding it to and from the lower end of the door opening, such means being operable, should the door stick or fail to slide open, to permit 35 the door to swing outwardly, whereby the merchandise which obstructs the door can be removed so as to permit the door to be slid open in the usual way. The improvements thus reside in means for permitting the door 40 to swing outwardly in emergency, as when the freight or merchandise falls against the door, wedging it tight.

A further object is the provision of a plate 45 hinged to the lower edge of the door and co-operable with a guiding and holding strip extending along the sill of the car, means being provided for securing said plate to the door, so that the door is ordinarily guided along said strip and held against the wall 50 of the car, said plate when released in case of emergency, permitting the door to swing outwardly away from the door opening.

It is also the object of the invention to 55 provide a door construction embodying the improvements above noted, and which, at the same time, will be comparatively simple

and inexpensive in construction, as well as being practical and efficient in use.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein—

Figure 1 is an outside elevation of the door embodying the improvements.

Figure 2 is an enlarged vertical section taken on the line 2—2 of Figure 1 through the lower edge portion of the door.

Figure 3 is an edge view of the upper portion of the door and hanger.

Figure 4 is a view similar to Figure 2 illustrating a modification.

The door 1 can be of wood or other suitable construction, and is suspended for sliding movement along the car wall and for swinging movement to and from said wall. Thus, the hinge plate or leaf 2 is secured to the outer side of the door near and spaced slightly below the upper edge of the door, said plate 2 extending substantially the width of the door, and being hinged, as at 3, to the lower edge of a hanger plate 4 also extending the width of the door, and provided at its upper edge with a T-head, the flanges of which are movable on rollers 5 mounted within the channels of the track 6 carried by the car wall and extending over the door opening and to one side thereof. This permits the door to be moved freely to and from the opening, and provides a wind and rain proof track and hanger, preventing rain, snow and sleet from entering the car above the door. It will be noted that the hinge 3 is at the outer side of the door below the upper edge thereof, preventing rain or moisture from passing through the hinge behind the door, and the lower portion of the hanger plate 4 is offset outwardly, as at 4^b, so that when the door 1 is swung inwardly to vertical position, the upper edge thereof bears against the plate 4 within the offset portion 4^b, to prevent the upper edge of the door and hanger plate from breaking or shifting outwardly.

The hinge permits the door to swing outwardly at its lower edge, when the door is released, for the purpose of removing the merchandise or freight

which obstructs the door to prevent the same sliding open in the usual way.

In order to hold the lower edge of the door against the car wall and to guide it for longitudinal movement along said wall, a plate 7 extending the width of the door 1 is hinged, as at 8, to the lower edge of the door, and a longitudinal strip or bar 9 is secured to the sill and is coextensive in length with the track 6, extending below the opening and to one side thereof. Plates or strips 10 and 11 are secured to the lower edge portion of the door, the plate 10 at the outer side, and the Z-plate 11 to the lower edge and rear side of the door, and the plate 7 is hinged to the plates 10 and 11. The strip 9 has its upper edge offset outwardly, to provide the upstanding flange 12, while the plate 7 is provided with a rearwardly or inwardly extending hook-shaped portion or flange 13 extending downwardly behind the flange 12 when the plate 7 is swung upwardly against the door 1, which is the normal position of the parts, as shown in full lines in Figure 2. Thus, the flange 13 sliding behind the flange 12, will guide the lower edge of the door and also retain it against the side of the car, in order that the door can slide open and shut in the ordinary way.

The plate 7 has one or more arms 14 extending from its free edge to bear against the door 1, for securing the plate 7 to the door in order to hold the flange 13 behind the flange 12. As a means for securing said arms to the door 1, nuts 15 are embedded in the door 1, and screws 16 are carried by the arms 14 and have handles 17 at their outer ends, whereby said screws can be threaded into the nuts for securing and holding the plate 7 against the door, although other equivalent means can be used for this purpose.

It is unnecessary to release the plate 7, excepting in case of emergency, when the freight or merchandise wedges against the door, preventing it from sliding open. In this case, the plate 7 is released from the door 1, and will swing downwardly, as seen in dotted lines in Figure 2, thereby raising the flange 13 upwardly from behind the flange 12, and permitting the door to swing open. The merchandise which obstructs the sliding movement of the door, can then be removed, and the door swung back against the wall, the plate 7 swung upwardly and secured to the door, and the door then slid open.

Another advantage in the use of the plate 7 and strip 9 resides in the fact that it prevents the leakage or escape of grain or other material past the lower edge of the door, and they also prevent the insertion of wires, knives, and other objects, up behind the lower edge of the door for tapping bags of sugar, or the like, for purpose of theft.

The improvements thus serve to prevent theft and leakage, as well as permitting the door to swing open when necessary.

A vertical stop 18 for the door 1 is provided at one side of the door opening as usual, and a stop 19 is carried by the car wall to limit the opening of the door. An ordinary locking or sealing device 20 can be used for holding the door 1 closed.

Figure 4 illustrates the use of the improvements with a sill S' of T-iron. Thus, the strip 9 is secured to the web of the sill under the outer flange, and the plate 7' has a portion 7'a extending at an angle rearward under the lower edge of the door 1 and 80 hinged, as at 8, to the lower edge of a plate 11' secured to the inner side of the door and extending below the lower edge thereof. In this form, the hinge 8 is at the inner side of the door, instead of the outer side, as in Figure 2, and the plate 7' is shaped to extend under the lower edge of the door and upwardly to overlap the outer side thereof. This permits the flanges 12 and 13 to be located below the outer flange of the sill. 90 Otherwise, the construction is about the same as illustrated in Figure 2.

Having thus described the invention, what is claimed as new is:

1. The combination of a car wall having an opening, a door to close said opening, means for suspending said door for sliding movement along said wall and for swinging movement away from said opening, a strip extending along said wall below said opening and having an upwardly extending flange, and a plate carried by the lower edge portion of and extending the width of the door, said plate being movable upwardly and downwardly relatively to the door and having a flange to move downwardly below the lower edge portion of the door behind the aforesaid flange to hold the lower edge portion of the door against and guide it along said wall.

2. The combination of a car wall having an opening, a door to close said opening, means for suspending said door for sliding movement along said wall and for swinging movement away from said opening, a strip extending along said wall below said opening and having an upwardly extending flange, a plate hinged to the lower edge portion of the door and having a flange to swing downwardly behind the aforesaid flange, and means for swinging said plate to move the flange thereof and hold it behind the first named flange.

3. The combination of a car wall having an opening, a door to close said opening, means for suspending said door for sliding movement along said wall and for swinging movement away from said opening, a strip extending along said wall below said opening and having an upwardly extending

flange, a plate hinged to the lower edge portion of the door to swing upwardly against the outer side of the door and provided at the hinge with a flange to swing downwardly 5 behind the aforesaid flange, and means for securing said plate to the door.

4. The combination of a car wall having an opening, a door to close said opening, a track extending over said opening, a hanger 10 extending the width of the door and suspended from the track for sliding movement, said hanger having its lower edge portion

overlapping the upper edge portion of the door on the outer side thereof, and hingedly connected to the outer side of the door below 15 the upper edge of the door, to enable the door to swing away from said opening, the upper edge of the door swinging adjacent to said hanger when the door is swung toward said wall, and means for holding the door 20 against said wall.

In testimony whereof I hereunto set my hand:

JOHN L. GUERRANT.
